DESIGN FOR A TENNIS BALL

Samuel Graham Ball, Streetly, England, assignor
to Dunlop Tire and Rubber Corporation, Buf-
falo, N. Y., a corporation of New York

Application June 9, 1937, Serial No. 69,758
In Great Britain December 23, 1936

Term of patent 14 years

To all whom it may concern:

Be it known that I, Samuel Graham Ball, a subject of the King of Great Britain, residing at Streetly, Warwickshire, England, have invented a new, original, and ornamental Design for Tennis Balls, of which the following is a specification, reference being had to the accompanying drawing, forming a part thereof.

Fig. 1 is a plan view of a tennis ball, showing my new design; Fig. 2 is a plan view rotated 90° about the horizontal axis of Fig. 1.

I claim:

The ornamental design for a tennis ball, as shown.

SAMUEL GRAHAM BALL.
